CLAIM

The ornamental design for a massage gun with charging base, as shown and described.

DESCRIPTION

FIG. 1 is a perspective view of a massage gun with charging base, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a charging base of the massage gun with charging base, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the massage gun with charging base.

The broken lines in the drawings depict portions of the massage gun with charging base that form no part of the claimed design.
